UNITED STATES PATENT OFFICE.

HARRY FERGUSON, OF NEW YORK, N. Y.

COVERING FOR SCREW-HEADS.

SPECIFICATION forming part of Letters Patent No. 416,329, dated December 3, 1889.

Application filed September 21, 1889. Serial No. 324,651. (No model.)

To all whom it may concern:

Be it known that I, HARRY FERGUSON, of New York, in the county and State of New York, have invented a certain new and useful Improvement in Coverings for Screw-Heads, of which the following is a specification.

My improvement is designed to so cover the heads of screws when they are engaged with wood or other material that they will not be exposed to view.

I will describe my improvement in detail, and then point out the novel features in a claim.

15 In the accompanying drawings, Figure 1 is a face view of a covered screw-head embodying my improvement, showing the same as engaged with a piece of wood. Fig. 2 is a vertical section of the piece of wood and of 20 the covering for the screw-head, the screw itself being shown in full lines. Fig. 3 is a detail view of one portion of the covering. Fig. 4 is a detail view of another portion of the covering. Fig. 5 is a detail view showing the portion of the covering shown in Fig. 3 as applied to the screw-head. Fig. 6 is a view similar to Fig. 5, but showing a modification. Figs. 3, 4, and 5 are on a larger scale than Figs. 1 and 2.

30 Similar letters of reference designate corresponding parts in all the figures.

In carrying out my improvement I employ a member A of the covering for the screw-head. The member A has upon its upper side a cylindrical opening a . The sides of this opening are formed by an annular cylindrical flange a' . The lower portion of the member A is provided about centrally with an opening a^2 .

40 In the examples of my improvement shown in Figs. 2, 3, and 5 the metal between the flange a' and the opening a^2 extends inwardly and downwardly at an angle. This is for the purpose of accommodating screw-heads having angularly-extending under sides, and the radius of the angle upon the member A is intended to correspond approximately with the radius of the angle upon the under side of a screw-head adapted to fit the same, so 45 that when the screw-head rests within the

member A it will fit the angularly-extending portion, substantially as shown in Fig. 5. The opening a^2 upon the lower side of the member A is intended to be of but slightly greater diameter than is the shank of the 55 screw upon which the covering is employed. When the screw is in place within the member A, the flange a' extends above the upper surface of the screw-head.

In the example of my improvement shown 60 in Fig. 6 the member A, instead of having an angularly-extending portion below the flange a' , has a horizontally-extending portion, which portion extends at approximate right angles to the flange a' before the parts 65 have been fully assembled. This is for the purpose of accommodating screw-heads having flat under sides.

In both examples of my improvement I employ a cap B, constituting the second member of the covering. As shown, this cap is hemispherical and hollow. When the screw-head has been placed within the member A and has been screwed into the wood or other material with which it is to engage, as shown 75 more clearly in Fig. 2, the member B is passed downwardly over the upper end of the screw-head and within the flange a' , the latter being of sufficiently greater diameter than that of the member B to admit of this. 80 When in such position, a suitable tool is employed to bend the flange a' over the edge of the member B, as shown more clearly in Figs. 1 and 2. The member B is thus effectively secured, while at the same time the screw-head 85 is fully concealed, as shown more clearly in Fig. 1.

If for any purpose it should be desired to remove the screw, it is but necessary to bend back the flange a' and remove the member 90 B. The screw may be then withdrawn by a screw-driver in the usual way.

By my improvement I provide a simple and effective means for concealing a screw-head and preventing the unsightly appearance which such screw-heads often present.

What I claim as my invention, and desire to secure by Letters Patent, is—

A covering for a screw-head, comprising 100 two members, one of which constitutes a re-

ceiver for the screw-head and is provided upon its upper edge with a circumferential flange, and the other of which is in the form of a cap, said two members being adapted to be secured together by turning the edges of the first-named member over those of the cap, so as to inclose and conceal the screw-

head after the driving of the screw, substantially as specified.

HARRY FERGUSON.
